Primary Examiner—Antoine Duval Davis

[57] **CLAIM**

The ornamental design for a blowgun with nozzle tip for attaching quick coupling accessories, as shown and described.

DESCRIPTION

FIG. 1 is a top, side and real perspective view of a blowgun with nozzle tip for attaching quick coupling accessories showing my new design;

FIG. 2 is a side elevational view thereof;

FIG. 3 is a front perspective view;

FIG. 4 is a bottom perspective view;

FIG. 5 is a top plan view;

FIG. 6 is a side elevational view opposite of that shown in FIG. 2;

FIG. 7 is a bottom plan view; and,

FIG. 8 is a rear perspective view from the bottom.
